UNITED STATES PATENT OFFICE.

RUDOLF KUSS, OF NEW YORK, N. Y., ASSIGNOR TO A. M. BOLLERMAN, INC., OF NEW YORK, N. Y., A CORPORATION OF NEW YORK.

AUTOMATIC MUSICAL INSTRUMENT.

1,283,220.

Specification of Letters Patent.

Patented Oct. 29, 1918.

Application filed November 11, 1916. Serial No. 130,695.

To all whom it may concern:

Be it known that I, RUDOLF KUSS, a subject of the King of Germany, and resident of New York city, borough of Manhattan, in the county of New York and State of New York, have invented certain new and useful Improvements in Automatic Musical Instruments, of which the following is a specification.

10 My invention has particular reference to improvements in striker mechanism of pneumatically operated devices for musical instruments, and has for its object to provide simple and efficient means for supporting the 15 striker pneumatics in such manner that they may be readily removed and replaced, as well as to permit ready access to the valves that control such pneumatics, and also to provide simple means for operation of such 20 pneumatics.

My invention comprises novel details of improvement and combinations of parts that will be more fully hereinafter set forth and then pointed out in the claims.

25 Reference is to be had to the accompanying drawings forming part hereof, wherein,

Figure 1 is a front elevation of a portion of an action chest and exhaust chest, the front wall of the action chest being partially 30 in section;

Fig. 2 is a section on the line 2, 2, in Fig. 1;

Fig. 3 is an enlarged section substantially on the line 3, 3, in Fig. 1;

35 Fig. 4 is a view looking from the right-hand side of Fig. 3, the front board of the action chest and the valve guides 14 being removed, and

40 Figs. 5, 6 and 7 are details hereinafter referred to.

At 1 is indicated the front board of an action chest, and at 2 are striker pneumatics supported by the action chest. I have illustrated the striker pneumatics as arranged in 45 tiers, it being understood that any suitable number of such pneumatics may be arranged in a row in each tier. One of the features of my invention is that for each horizontal row of pneumatics there is a corresponding relatively narrow board 3, 4, 5, of the action chest, said boards being placed on edge and superimposed, and spaced from board 1 to provide an exhaust space 6 between such

boards 1 and 3, 4, 5. The boards 3, 4, 5, may be secured together by glue and by screws or bolts ⁵⁵ a passing therethrough. I have shown longitudinal strips 7, 8, that are secured respectively as by screws to the upper and lower boards 3 and 5 as well as end strips 9 extending across the boards 3, 4, 5 and secured thereto as illustrated in Fig. 4, the front board 5 being secured over said strips as by screws, providing the space 6. The blocks 2^a of the striker pneumatics are secured to the corresponding board 3, 4 or 5 ⁶⁵ by screws indicated at 10, whereby said blocks may be readily removed. Blocks 2^a have channels 2^b communicating respectively with the ports 2^c of the corresponding pneumatics and with passages 11 drilled in the ⁷⁰ corresponding outer faces of the boards 3, 4, 5. The boards 3, 4, 5 also have vertical passages 12 drilled from their edges inwardly, the outer orifices of which passages 12 of one board are closed by the opposing ⁷⁵ edge of the next board. This construction affords a simple, cheap and efficient arrangement for providing passages in the boards 3, 4, 5, for communication with the corresponding pneumatics, and enables ready access to such passages by merely disassembling boards 3, 4, 5. The inner ends of the ⁸⁰ passages 12 each communicate with a corresponding recess 13, bored into the boards 3, 4, 5 from their inner faces, the outer portions of the recesses 13 being reduced at 13^a. At 14 are perforated valve guides of any ⁸⁵ usual or suitable construction, shown seated in the ends of recesses 13 at chamber 6, and at 15 are perforated guide strips secured, as ⁹⁰ by screws 16 (Fig. 6), to the boards 3, 4, 5, across the corresponding reduced recesses 13^a to permit the admission of air to the recesses 13. Pairs of valves 16 and 17 are shown mounted upon stems 18, said valves being ⁹⁵ located within the corresponding recesses 13. Said valves are so spaced upon stems 18 that the valves 16 will close against the openings of seats 14 to prevent admission of air to chamber 6 the valve 17 then admitting air to the pneumatics through recesses 13. Said valves are also so arranged that when moved by reason of air passing through the tracker orifices, the valves 17 will close the corresponding reduced recesses 13^a and valves 16 ¹⁰⁰ will open the ports of seats 14 to the cham-

ber 6 to cause exhaust through recesses 13 and passages 12, 11 and 2^b from the corresponding striker pneumatics. The front board 1 is provided with a recess 19 opposing 5 each valve stem, over each of which recesses is secured a movable member or diaphragm 20 to coact with the corresponding valve stem 18 to push the latter to shift the valves. In the front board 1 passages 21 are drilled 10 to communicate with the upper horizontal row of recesses 19, and correspondingly passages 22 and 23 are drilled in board 1 to communicate respectively with the middle and lower horizontal rows of recesses 19, the 15 passages 21, 22 and 23 having different lengths to reach to the corresponding rows of recesses 19. The upper or outer ends of the passages 21, 22, 23 are closed by plugs 24. The upper portions of the passages 21, 22, 23 20 also communicate with laterally disposed passages 25 drilled in the inner face of board 1 (Figs. 1 and 3). Passages 26 are drilled transversely through the upper strip 7 to register with the passages 25 (Fig. 3), and 25 in the corresponding face of board 3, passages 27 are drilled to register with the passages 26. Passages 27 may be formed by drilling into the inner and upper surfaces of the board 3 to meet within the same, as illustrated in Fig. 3. The arrangement of the 30 passages just described provides communication to each of the corresponding recesses 19, from board 3 through strip 7 and through board 1, from the tubes 7 that are 35 to be connected with the orifices of a tracker bar of a pneumatic player mechanism in any well known manner.

At 28 is indicated a wippen, at 29 a hammer, and at 29' a jack of the action of 40 a piano, a striker pneumatic 2 being provided as usual for each of the wippens, all of which may be of any suitable construction operating in a well known manner for striking strings of a piano. Above the wippens is a rail 30, which may be carried upon spaced arms 31 secured to board 3, as by bracket 32, (Fig. 3) and at 33 are adjustable stops, as of felt, carried by screws 34 working in threaded apertures in rail 50 30, there being one of such stops above each wippen to limit its movement by the corresponding striker pneumatic. By adjusting the stops 33 up or down the movement of a wippen by the corresponding striker pneumatic may be regulated. The stationary board 2^a of each striker pneumatic is provided with a guide 35 having a guiding aperture 35^a receiving a slidable stem 36 adapted to operate the corresponding wippen, said stem being shown provided with a threaded rod 37 operated by the movable board 2^b of the corresponding pneumatic. 60

I have shown the rod 37 as operative in a threaded aperture in a short shaft 38

(Figs. 3 and 7), the ends of which shaft 65 are journaled in apertures in the forked end of a support 39 secured on the movable board 2^b of the corresponding striker pneumatic. Shaft 38 may be made of any suitable material, such as leather, to prevent noise and withstand wear. By rotating stem 36 and rod 37 the operating position thereof with respect to the wippen and the movable board of the striker pneumatic may be regulated, and as said board moves 70 75 the shaft 38 may rock in its bearings.

The action chest comprising the boards 1, 3, 4, 5, etc., is shown connected at one end to a chest 40 in communication with space 6 of the action chest through the relatively narrow passage 41. By means of pipe 42 chest 40 may be connected with an exhaust chest 43 shown provided with a bellows 44 and pedal 45 in an ordinary manner, for inducing exhaust through the 80 85 action chest.

The action chest may be detachably supported in a musical instrument or piano in any suitable manner. By means of my improvements, whenever it is desired to gain 90 access to the valves 16, 17, or the diaphragms 20, or to remove any of the striker pneumatics, it is merely necessary to remove the front board 1 of the action chest, whereupon the valve stems 18, the seats 14, and the screws 10 may be readily reached, whereby any of the valves may be removed, or the striker pneumatics may be unscrewed and removed as desired. It also will be understood, when the action chest is out of the piano that by removing the separate 95 boards 3, 4, 5, the striker pneumatics attached thereto may be removed therewith bodily. By forming the passages 11, 12 and chambers 13 in the separate boards 100 105 3, 4, 5, as described, the construction of this portion of my invention is simplified and cheapened, and, since said boards may be secured together by screws, as before described, the boards may be removed and replaced expeditiously. While I have illustrated three boards and tiers of recesses 13 arranged in three horizontal rows, it will be understood that the number of rows and the number of such recesses in a tier may 110 115 be varied in accordance with the number of the boards, such as 3, 4, 5, as are secured together in the manner stated.

Having now described my invention what I claim is:—

1. In an action chest, the combination of a board, a plurality of superimposed boards, means spacing the first and last named boards apart providing a space therebetween, the second named boards having recesses, passages leading from the edges of said boards to said recesses and covered at their outer ends by adjacent boards, and 120 125

pneumatics secured upon the outer faces of said boards, the latter having passages for communicating with the pneumatics and with said passages in the boards.

5 2. In an action chest the combination of a board, a plurality of superimposed boards, means spacing the first and last named boards apart providing a space therebetween, the second named boards having recesses, passages leading from the edges of said boards to said recesses and covered at their outer ends by adjacent boards, and pneumatics secured upon the outer faces of said boards, said boards being provided 10 with passages entering said faces and communicating with the pneumatics and with the first named passages in said boards.

3. In an action chest, the combination of a board, a plurality of superimposed boards, 20 means spacing the first and last named boards apart providing a space therebetween, the second named boards having recesses, passages leading from the edges of said boards to said recesses and covered at their outer ends by adjacent boards, pneumatics secured upon the outer faces of said boards, the latter having passages for communicating with the pneumatics and with said passages in the boards, valves provided 25 with stems in said recesses, and guides for said stems, said first named board having pneumatically operating means to operate said valves respectively.

4. In an action chest, the combination of a board, a plurality of superimposed boards, 35 means spacing the first and last named boards apart providing a space therebetween, the second named boards having recesses, passages leading from the edges of said boards to said recesses and covered at their outer ends by adjacent boards, pneumatics secured upon said boards, the latter having passages for communicating with the pneumatics and with said passages in 40 the boards, valves provided with stems in said recesses, guides for said stems, the first named board having recesses, and movable members opposing said recesses and said stems, said board having channels communicating with said recesses.

5. In an action chest, the combination of a board, a plurality of superimposed boards, means spacing the first and last named boards apart providing a space therebetween, the second named boards having recesses, passages leading from the edges of said boards to said recesses and covered at their outer ends by adjacent boards, pneumatics secured upon said boards, the latter 55 having passages for communicating with the pneumatics and with said passages in the boards, valves provided with stems in said recesses, guides for said stems, the first named board having recesses corresponding

to the recesses first named, and diaphragms 65 over said recesses to operate said stems, said board having channels communicating respectively with its recesses.

6. In an action chest the combination of a board, a plurality of superimposed boards, 70 means securing said boards together on edge, strips spacing the first and last named boards apart providing a space therebetween, the second named boards each having a row of spaced recesses and having passages leading from the edges of said boards to said recesses, said passages being covered at their outer ends by adjacent boards, and pneumatics secured upon said boards corresponding to said recesses, said boards having 75 recesses communicating with the pneumatics and with said passages in the boards.

7. In an action chest the combination of a board, a plurality of superimposed boards, means securing said boards together on edge, 80 strips spacing the first and last named boards apart providing a space therebetween, the second named boards each having a row spaced of recesses and having passages leading from the edges of said boards to said recesses, said passages being covered at their outer ends by adjacent boards, pneumatics secured upon said boards corresponding to said recesses, said boards having channels 85 communicating with the pneumatics and with said passages in the boards, valve stems in said recesses, valves upon said stems spaced apart in said recesses, the first named board having recesses opposing said stems, diaphragms over said recesses to 90 coact with said stems, said board having passages respectively communicating with said recesses and opening through a face of the board, one of said strips having passages 95 communicating with the last named passages, and means to connect tubes to said passages.

8. In an action chest the combination of a board, a plurality of superimposed boards, means securing said boards together on edge, strips spacing the first and last named boards apart providing a space therebetween, the second named boards each having a row of spaced recesses and having passages leading from the edges of said boards to said recesses, said passages being covered at their outer ends by adjacent boards, pneumatics secured upon said boards corresponding to said recesses, said boards having recesses 100 communicating with the pneumatics and with said passages in the boards, valve stems in said recesses, valves upon said stems spaced apart in said recesses, the first named boards having recesses opposing said stems, diaphragms over said recesses to coact with 105 said stems, said board having passages respectively communicating with said recesses and opening through a face of the board,

one of said strips having passages communicating with the last named passages, one of the first named boards having passages communicating with the passages in said strip, and means to connect the passages of said last named board with a tracker.

Copies of this patent may be obtained for five cents each, by addressing the "Commissioner of Patents, Washington, D. C."

Signed at New York city, in the county of New York, and State of New York, this 4th day of October, A. D. 1916.

RUDOLF KUSS.

Witness:

MARIE F. WAINRIGHT.
